UNITED STATES PATENT OFFICE.

CHARLES H. MERRY, OF NEW ORLEANS, LOUISIANA.

BALING-CASE.

SPECIFICATION forming part of Letters Patent No. 243,940, dated July 5, 1881.

Application filed April 30, 1881. (No model.)

To all whom it may concern:

Be it known that I, CHARLES H. MERRY, of New Orleans, Louisiana, have made a new and useful Improvement in Baling-Cases, of which 5 the following is a full, clear, and exact description, reference being had to the annexed drawings, making part of this specification, in which—

Figure 1 is a side elevation of the improved 10 case; Fig. 2, an end elevation of the case; Fig. 3, a vertical section taken on the line $x\ x$ of Fig. 4, the wheels not being shown; Fig. 4, a plan, and Fig. 5 a horizontal section taken on the line $x'\ x'$ of Fig. 1.

15 The same letters denote the same parts.

This improvement is adapted more especially 20 to cases for baling cotton. It has relation mainly to the operation of the doors at the foot of the case, where the bale is removed.

25 There are at present three plans commonly in use of operating these doors. One is to hinge the doors at the bottom, in which case the top of the door falls outward, covering a floor-space, in practice, of three feet at each side of the case. The workmen must stand away as the doors are being opened, and in applying the ties 30 they are obliged to stand upon the doors, which are on a level with the bottom of the bale. This causes the operation of affixing the ties to be slow and laborious. Another mode is 35 hinging the door at the side, which is objectionable from its requiring so large a space—in practice four and one-half to six feet on each side—to open the doors in, and, as in the former case, the workmen must stand away until the doors are fully opened. The third plan is where 40 the doors are not hinged, but are removed and put aside from the case—a slow operation, requiring, in practice, the strength of at least two workmen.

To enable the doors in question to be operated in much less time and much more easily, and without taking up the room immediately around the case, is the aim of the present improvement.

45 Referring to the drawings, A represents a baling-case having the improvement, and, saving which, of the usual construction. B B' represent the doors at the foot of the case.

50 When the case is closed the doors are held in place by dropping the lower edge, b, within a shoulder, a, upon the case and confining the

upper edge, b', by the latches C C. To release the door the latches are turned on the pivots c c, as indicated by the dotted lines, leaving 55 the upper end of the door free. The door is then, and conveniently by the handle b², drawn outward from the case sufficiently to clear it, whereupon the counter-balances D D, which are connected with the door by means of the 60 cords d d passing over the pulleys d' d', act to balance the doors, enabling them to be readily and rapidly lifted directly upward, as indicated by the dotted lines, and out of the way of the operatives, to be drawn down again when the 65 case is to be closed. In this manner the doors can be easily managed by a single operative and in comparatively much less time.

The latches can be applied at any suitable 70 points around the edge of the door, as desired.

The improvement is designed more particularly to be used in connection with the baling-cases shown in the patent granted me July 20, 1880, and which, being intended to be used upon a trackway, necessitates the use of wheels, 75 such as E E. To prevent the strain of the press from coming on the wheels, the latter are hung upon the bent axles e e, and by means of the levers e' e' the axles e e can be turned in 80 their journals e², and the wheels E thereby turned up and the case allowed to rest directly upon the floor during the pressing of the bale. When the case is to be removed the wheels are turned down and the case raised from the 85 floor. As the case, in practice, is very heavy, an increased leverage may be obtained by attaching a cord or chain, F, to the lever e' and 90 passing it around a sheave, f; upon the case A, and thence around a windlass, f', which is also conveniently attached and held in a bracket, f², upon the case A. By turning the crank f³ the cord is wound upon the windlass and the lever e' drawn up toward the case, and the latter raised upon the wheels E. The axles e e upon the opposite ends of the case are connected by rods e³, enabling one lever e' to operate both pairs of wheels.

I claim—

1. A baling-case having the door B or doors B B' counterbalanced, and when closed confined laterally to the case, for the purpose described.

2. The combination of the baling-case A, door B, fastenings C a, counter-balances D D,

cords d d , and pulleys d' d' , substantially as described.

3. The combination of the case A, door B, pivoted latches C C, and the shoulder a , substantially as described.

4. The combination of a baling-case, A, the wheels E E, and the bent axles e e , as and for the purpose described.

5. The combination of the case A, wheels E E, axles e e , lever e' , cord F, sheave f, and windlass f' , substantially as described.

CHARLES H. MERRY.
